UNITED STATES PATENT OFFICE.

IRWIN JAMES FRENCH, OF PITTSBURGH, PENNSYLVANIA, ASSIGNOR OF THREE-FIFTHS TO ALFRED C. GOOD, OF WILKINSBURG, PENNSYLVANIA.

BOILER.

Application filed January 11, 1924. Serial No. 685,709.

To all whom it may concern:

Be it known that I, IRWIN J. FRENCH, a citizen of the United States, residing at Pittsburgh, in the county of Allegheny and State of Pennsylvania, have invented certain new and useful Improvements in Boilers, of which the following is a specification.

My invention relates to steam and hot water boilers and it has especially for its object the provision of a base and grate structure in which means are provided for the easy repair or replacement of the grate; the invention further has for its object to provide a base and grate structure for boilers in which the parts may be assembled without the use of tools and held in place without the use of bolts and nuts.

In general, the invention has for an object to provide an inexpensive, simple and efficient base and grate structure of the character specified which is especially adapted for use with boilers having water tubes passing through the fire box such as shown in my application filed December 12, 1922, Serial No. 606,368.

Again it is an object of the invention to provide a grate structure of such cooperative arrangement of parts that only the fine ashes resulting from the combustion can sift through to the ash box when the grate elements are turned.

A still further object is to provide a grate structure consisting of several elements, each independently operative and each being composed of several sub-units mounted on a grate bar in such a manner that any one of the units may be replaced or repaired without disturbing the remainder.

40 In the drawings:

Figure 1 is a cross section of a boiler with my invention in use.

Figure 2 is a longitudinal section of a portion thereof.

45 Figure 3 is a detail perspective view of the base, side, front and back plates.

Figure 4 is a detail perspective view of one of the base-interlocking and grate bar supporting elements.

50 Figure 5 is a detail horizontal section of a portion of the structure.

Figure 6 is a detail perspective view showing one of the grate "squirrel cage" elements.

55 In the drawings, in which like numerals of

reference indicate like parts in all the figures, 1 and 2 designate the front and back walls and 3 the side walls of the base structure. These are provided with flanges 4 on which the boiler body 13 rests, the boiler body 13 60 inclosing the fire box 14.

The front plate 1 of the base has an opening 5 to which is fitted an ash pit door 15, see Figure 2.

Each of the plates 1, 2 and 3 at its corners 65 is provided with flanges 6 which cooperate with the faces 7 to receive the dove-tail members 11 which are joined in pairs, as at 10, the pairs being joined by the grate bar supports 8, the latter having the notches or recesses 9 for the grate bar bearing ends 16 to rest in.

When the plates 1, 2 and 3 are brought together and the grate bar supports 8 located with their dove-tail elements 11 in the dove-tail recesses provided between the lugs 6 and faces 7, the base plates will be held interlocked, as it were, it being understood that in mounting the furnace it is customary to set the bottom edge of the base in concrete as 75 indicated in Figure 1, and this, together with the weight of the boiler upon the flange 4, assists in holding the parts interlocked. With this arrangement the plates 1, 2 and 3 will be held together without the use of 80 screws, bolts, or other securing devices.

The front wall 1 is provided with grate bar holes or passages 12 through which the grate bars 17 may be inserted, the holes 12 being of a diameter slightly more than the 90 greatest diameter of the grate bars 17 so that these bars may be inserted and withdrawn through the holes 12 before or after the furnace is assembled.

As shown best in Figures 2 and 6 each 95 grate unit consists of a bar 17 of rectangular or square cross section with cylindrical bearing portions 16-18 at the ends and a squared portion 19 at the extreme or outer end to which a shaker lever (not shown) may be 100 applied in the usual manner. A collar 20 may be cast or formed on the bar 17 at its front to prevent the bar being inserted too far into the ash pit and act as a stop against the bar being shoved in when the shaker lever 105 is applied. On each bar 17 is located one or more cage elements. These cage elements comprise heads 21 united by slats 22, the heads 21 being provided with square or rectangular openings 23 to fit on the bar 17. A 110

sufficient number of cages are assembled on a bar 17 to extend from the front to the back of the fire box 14 of the furnace 13 as shown in Figure 2.

- 5 The several units of the grate are arranged so as to lie with their peripheries in close approximation, see Figure 1, in order that only the fine ashes may pass. The slats 22 of each cage are also relatively close together so as to allow the fine ashes to pass while holding back the larger coal.

In practice the shaker lever is applied to the end 19 of a bar and the bar turned completely around or merely oscillated in the wall, thus causing the ash to pass down between the slats of the bar into the cage and then again between the slats of the bar out of the cage into the ash pit, as well as to feed down between adjacent grate units.

- 20 Should any of the grate units or any section of the grate units burn out or require replacement it is a simple matter to draw out the particular bar 17 of that unit and drop off the defective grate cages. New ones may be then held in position and the bar 17 threaded and the same restored to its position on the members 8.

From the foregoing it will be seen that I have provided a simple and effective construction for the purposes intended, which can be manufactured at a low cost and in which replacements can be made without the necessity of taking the furnace apart or of using tools for disconnecting the grate elements. The entire operation of changing the grate elements can be made with the fire in the fire box and operations can be conducted through the ash pit.

- 25 In this application I make no claim to the furnace structure per se or the combination between the furnace body and the grate and base structure as that constitutes the subject matter of my original application hereinbefore referred to, this application being a continuation in part of the original application.

30 From the foregoing description, taken in connection with the accompanying drawings, it is thought the complete construction, operation and advantages of my invention will be clear to those skilled in the art to which it relates.

What I claim is:

1. In a boiler of the character described, an ash pit base composed of opposite end and opposite side members, one of the end members having an ash pit door and apertured for the passage of the front journals of the grate bars, the said ends and side sections having aligning dove-tailed clamping portions whereby the said ends and sides are removable, supporting frames each adapted for being located crosswise of and inside its respective end of the base, each of said supporting frames having its opposite ends bent inwardly to form dove-tailed

heads for interlocking with the dove-tailed clamping portions on the adjacent ends of the main and end portions of the base, the said frames having socket portions along their upper edge which constitute bearings 70 for the journals of the grate bars.

2. In a boiler of the character described, an ash pit base composed of opposite end and opposite side members, one of the end members having an ash pit door and apertured for the passage of the front journals of the grate bars, the said ends and side sections having aligning dove-tailed clamping portions whereby the said ends and sides are assembled, supporting frames each 75 adapted for being located crosswise of and inside its respective end of the base, each of said supporting frames having its opposite ends bent inwardly to form dove-tailed clamping portions on the adjacent ends of 80 the main and end portions of the base, the said frames having socket portions along their upper edge which constitute bearings for the journals of the grate bars, the said dove-tailed portions of the supporting 85 frames being hollow and vertically slotted.

3. In a boiler, a base and grate structure comprising front, back and side base plates with flanges inwardly projecting in a plane below the upper edge of the plates, plate 90 interlocking elements including grate sustaining bars having bearing portions, one of said base plates having grate bar apertures, grate bars insertible longitudinally through said apertures and adapted to rest 100 on said grate bar supports, grate elements threaded on said bars and adapted to turn with the same, said bars being freely rotatable in their bearings.

4. A boiler base and grate structure, comprising front, back and side base plates adapted to constitute a rectangular base, said plates having lugs adjacent to the ends thereof constituting dove-tail sockets, grate bar supports having dove-tail elements to 105 cooperate with said sockets, one of said plates having grate bar openings, grate bars adapted to be inserted through said openings and to lie in bearing recesses in said grate bar supports, grate elements threaded 110 on said grate bars, each of said grate elements comprising cylindrical slatted cages.

5. A boiler base and grate structure, comprising front, back and side base plates adapted to constitute a rectangular base, 115 said plates having lugs adjacent to the ends thereof constituting dove-tail sockets, grate bar supports having dove-tail elements to cooperate with said sockets, one of said plates having grate bar openings, grate bars adapted to be inserted through said openings and to lie in bearing recesses in said 120 grate bar supports, grate elements threaded on said grate bars, each of said grate elements comprising cylindrical slatted cages, 125 130

- each of said cages comprising heads apertured to fit on the bars, and slats connecting adjacent pairs of heads.
6. In boilers, a hollow base that constitutes the ash pit of a boiler and upon which the bottom edge of a boiler body is supported; the corners of the base having flanged sockets, grate supporting frames each having oppositely disposed pendent members for interlockably engaging the flanged sockets in the base, said supporting frames having bearing sockets, a grate structure composed of a plurality of parallel longitudinal grate bodies, each of which comprises cylindrical grate members, each of said members having an axial bore and a grate bar on which the cylindrical grate members are slidably engaged, said bar having opposite end journals for engaging the socket bearings in the grate supporting frames and having their front ends shaped to receive a grate shaker for the purposes described.
7. In boilers, a hollow base that constitutes the ash pit of a boiler and upon which the bottom edge of a boiler body is supported, the corners of the base having flanged sockets, grate supporting frames each having oppositely disposed pendent members for interlockably engaging the flanged sockets in the base, said supporting frames having bearing sockets, a grate structure composed of a plurality of parallel longitudinal grate bodies, each of which comprises cylindrical grate members, each of said members having an axial bore and a grate bar on which the cylindrical grate members are slidably engaged, said bar having opposite end journals for engaging the socket bearings in the grate supporting frames and having their front ends shaped to receive a grate shaker, said grate bars having collars to limit their longitudinal movement when the shaker is applied.

IRWIN JAMES FRENCH.
